UNITED STATES PATENT OFFICE.

CHARLES FOLSON, OF CAMBRIDGE, MASSACHUSETTS.

BOOK-CLASP.

Specification of Letters Patent No. 13,166, dated July 3, 1855.

To all whom it may concern:

Be it known that I, CHARLES FOLSON, of Cambridge, and county of Middlesex and State of Massachusetts, have invented a certain new and useful Book-Clasp, of which the following is a full, clear, and exact description, reference being had to the accompanying drawings, making part of this specification.

10 Figure 1 is a view of the clasp; Fig. 2, a view of a book having two of the clasps attached.

Book clasps as heretofore made can only be used upon those books to which they are 15 permanently applied by the binder.

The object of my invention is to produce a clasp that may be instantaneously applied to books already bound, and may be adjusted to those of any size or thickness.

20 My improved clasp is particularly applicable to folios of large size which otherwise without assistance are unable to stand by themselves.

To enable others skilled in the art to make and use my invention I will proceed to describe the same.

A, B, are strips of sheet metal bent at right angles as seen in the drawings, one of them being furnished with a slot *a*, and the other with a tightening screw *b*, by which the two may be secured together, to accommodate the clasp to books of different sizes. It is placed upon the book in the manner represented in Fig. 2 by which means the most cumbersome folio may be made to stand upright and firm as when secured by permanent clasps.

What I claim as my invention and desire to secure by Letters Patent is—

The within described book clasp, constructed and operating in the manner substantially as set forth.

CHARLES FOLSON.
